ANDRÉ LERY, OF PARIS, FRANCE, ASSIGNOR TO ATELIERS J. CARPENTIER, OF PARIS, FRANCE, A CORPORATION OF FRANCE, AND COMPAGNIE FRANÇAISE POUR L'EXPLOITATION DES PROCÉDÉS THOMSON-HOUSTON, OF PARIS, FRANCE, A CORPORATION OF FRANCE

TELEGRAPHIC SYSTEM

Application filed March 27, 1929, Serial No. 350,415, and in France March 27, 1928.

The object of the present invention consists in the provision of means for eliminating the action of parasites on the synchronizing signals which are periodically sent out by the transmitting station of a telegraphic system, and are known as "correction signals."

The present invention is particularly applicable to telegraphic apparatus of the Baudot and similar types, and the arrangement hereinafter described eliminates, in a very effective manner, all disturbances of the synchronism resulting from the action of parasites.

It is known that in order to obtain the synchronism of distributors, such as of the rotary type, in Baudot and similar telegraphic systems, correction signals are employed, each of which is composed of a working current followed immediately by a resting current, transmitted regularly at each revolution by one of the distributors. This resting current, which merely serves to define the working current, is employed in wired telegraphy; in wireless telegraphy it is replaced by a local current which is intended to return the telegraphic relays rapidly to their positions of rest. The distributor transmitting these correction currents (correcting distributor) rotates at the normal speed; the distributor which receives them (corrected distributor) rotates slightly faster.

As a result of this difference of speed, the correction current is applied successively to each of the contacts of the corrected distributor. When it arrives at the special contact, called the "correction contact," it actuates an electromagnet which starts the correcting mechanism which retards the brushes of the corrected distributor by an angular quantity ϵ , which is greater than that which these brushes gain at each revolution of the distributor due to the difference of the speeds of the correcting and corrected distributors.

When the brushes, after several revolutions, have regained the angle ϵ , lost by the operation of the correcting apparatus, this latter acts again, and so on, so that the brushes are maintained in phase with a maximum displacement equal to the correction angle ϵ . This angle ϵ is determined by con-

struction, and is chosen small enough not to interfere with the functioning of the system.

It is possible for parasitic currents to operate the correcting mechanism instead of the working currents, especially in radio telegraphic systems. In the case where a parasite causes the correction mechanism to operate in an inopportune manner, the angle ϵ is increased by a fraction, and if this occurs several times in succession, the synchronism is lost. It is seen that if the parasites are frequent, it is necessary to protect the correcting system against this class of disturbance.

The arrangement hereinafter described by way of example, makes use of the fact that parasites are received in a haphazard fashion whilst the normal correction currents follow in a regular sequence. The arrangement is interposed between the correction contact and the correcting electromagnet, and operates in such a manner that it only allows the correcting electromagnet to act when the correcting current has been applied three consecutive times to the correction contact.

The accompanying drawings represent, by way of example and without limiting the invention, an arrangement constructed in accordance with the invention.

Fig. 1 diagrammatically shows the positions of the brushes of the distributor at the receiving station during several successive revolutions.

Fig. 2 represents the arrangement of the devices for protecting the correction apparatus.

Fig. 3 shows a detail of one of these devices.

If a telegraphic system is used in which the effect of parasites is eliminated by repeating the signals, by storing them and by automatically sorting them, the automatic repetition of the correction signals will also be effected.

In accordance with the present invention the speed of the corrected distributor is regulated in such manner that the correction functions with a certain periodicity, acting once in every m revolutions. Moreover, the correcting signals must be received n times to operate the correcting mechanism.

once, and it is necessary that m be greater than n .

When three correction signals are stored up before causing them to act on the correcting devices, the speed of the corrected distributor is regulated in such manner that the correction apparatus functions, for example, once in every five revolutions of the distributor.

10 In Fig. 1, the correction contact is represented by 10. The brushes of the distributor at the receiving station, which turn in the direction of the arrow, occupy, after correction, the position "a," after the first revolution the position "b," and after the second revolution the position "c." The correction currents transmitted at each revolution of the brush at the transmitting station remain inactive, since the brushes of the receiver 20 have not yet reached the contact 10.

After the third revolution, these brushes occupy the position "d." The local circuit of the correction system is then closed but, in accordance with the invention, the impulse-transmission must be made several times (three times in the example considered) to be effective. The first correction impulse is therefore stored by an arrangement which will be described later. The following impulse, which is received at the 25 fourth revolution when the brushes are in the position "e," is similarly stored, and it is only the third impulse, which is received at the fifth revolution when the brushes are 30 in the position "f," which produces the correction by returning the brushes to the position "a," that is to say displacing them backwards through the angle ϵ .

The apparatus which will be described is 40 arranged so that the correction can only be produced by a succession of three consecutive impulses. Therefore, if a parasite current arrives at the correction contact, the chances that another parasite will arrive at 45 the following revolution are very small, and disturbances will not be produced. It would be just the same, however, if a parasite arrived twice in succession at the correcting contact, since the correcting electromagnet 50 is only influenced when the current arrives three times in succession.

The arrangement for protecting the correction apparatus which operates according to the above principles, that is to say, which 55 operates the correcting electromagnet when the correction current arrives on the correction contact during three successive revolutions of the brushes, may be realised in the following manner.

60 On the same base (Fig. 2) are grouped three electromagnets 1, 2 and 3, and the commutator devices which control their armatures.

The telegraphic currents of the wireless 65 telegraphic station arrive at the terminals

18. The correction currents, coming from the correction contact 10, actuate the electromagnet 1 when the commutator 6 is at rest, but they are directed towards the correcting electromagnet 4 when the commutator 6 is 70 displaced by the notched rod 7. The electromagnets 2 and 3 are actuated, either one or the other, by a local current transmitted at each revolution by the brush of the ring 75 r of the distributor. The commutator 5 directs the local current either towards the electromagnet 2, or towards the electromagnet 3.

The armatures of the electromagnets 1 and 2 are mutually locked by the detents 12 and 80 13, so that each remains in the attracted position until the other has operated in its turn.

A notched rod 7, urged towards the right by the spring 19, can occupy three positions in the longitudinal direction.

85 A detent 8, fixed to the armature 14 of the electromagnet 2, pushes the rod and causes it to advance one notch from right to left each time the electromagnet 2 is operated. The armature of the electromagnet 3 carries an extension 9 which operates as a retaining catch for the rod. In the position of rest, it is maintained in position on the notch on which the action of the armature of the electromagnet 2 has placed it. When it is operated by its electromagnet 3, it releases the rod which then returns to its initial position 95 towards the right, pushed by the helical spring 19.

The detent 8 is represented in Fig. 3. It is 100 displaced between two fixed stops 15 and 16, engagement with which causes its left extremity to be lowered. This latter is raised, in the intermediate position, by the counterweight 17 and by a spring 20.

105 The action of the arrangement is easily understood. During the periods when the correction contact 10 sends no current, the correction apparatus is not operated. The electromagnet 2, having been actuated once by the regular current coming from the contact 11 of the local circuit, keeps its armature in the attracted position, locked by the armature of the electromagnet 1 which is not excited. 110 At the following revolutions, the regular current of the contact 11 is directed by the commutator 5 towards the electromagnet 3, the armature of which is periodically operated 115 and disengages the rod 7 which returns to its initial position towards the right.

If a correcting current—normal or parasitic—appears, it is directed by the commutator 6 to the electromagnet 1. This latter, 120 in attracting its armature, unlocks the armature of the electromagnet 2 which is immediately set in movement by the local current coming from the contact 11 and which causes the rod 7 to advance one notch towards the 125 130

left, at the same time locking itself again by the armature of the electromagnet 1.

At the next revolution, if a correction current arrives, it operates in the same way as the preceding one. The same movements are reproduced and the rod is advanced a second notch towards the left.

At this moment the rod acts on the commutator 6, it opens the circuit of the unlocking electromagnet 1, and closes the circuit of the correcting electromagnet 4, so that, when the correction current arrives for the third time, at the following revolution, it actuates the correcting electromagnet and the correction is made.

The local current supplied by 11, which follows the correction, is conducted towards the electromagnet 3, which releases the rod 7 which returns to its initial position towards the right. The work effected by the local current may also be obtained by means of a lever and a cam mounted on the spindle of the brush-carrying arm.

Each time that the correction current, either because it has not been sent by 10 or because it has just been acting on the correcting electromagnet 4, does not pass through the electromagnet 1, the local current, which is the next to operate during the same revolution, operates the releasing electromagnet 3 and the rod 7 returns to its initial position, whatever has been the position it has just been occupying.

If parasites have been able to displace the rod 7 one or two notches, their action will be neutralized at the next revolution if a new parasite or a regular correction current does not arrive at the same relative instant, as has already been described.

The efficiency of the system may be estimated by submitting it to the calculation of probabilities, by assuming, for example, a hypothetical case, in which the parasites have a frequency equal to 40% of that of the working currents, or, which is the same thing, to 20% of the number of contacts of the distributor.

Without a protector, the correction would be made once every five revolutions by the parasite current. This current would take the place of the normal correction current of the same frequency, and the synchronism would soon be put out of order and eventually lost.

If the protector comes into action, the parasites arriving on the correction contact, no longer affect the correcting electromagnet except when they appear at three consecutive revolutions of the brush. But it can be seen from the drawing that the correction contact is occupied three times out of five by the normal correction current. It is thus only exposed to parasites twice in every five revolutions. Besides, if the parasite arrives when the normal current finishes at the ex-

treme position in front of the correction contact, its disturbing effect will be neutralized at the next revolution. On the whole, the correction contact is only exposed once in every five revolutions, and the effect of the disturbance would be to advance, by one revolution, the operation of the correction mechanism, which corresponds to the increase of the angle ϵ by $\frac{1}{5}$ of its value. This disturbance could take place at each 5° turns, but the result would be insignificant. To obtain a double disturbance, that is equal to $\frac{2}{5} \epsilon$, an aggregate of 5^4 revolutions would be necessary. To really disturb the synchronism, it would be necessary for the disturbance to obtain a value at least equal to ϵ , which would only occur on the average at each 5^{10} revolutions, i. e. at each 9,765,625 revolutions.

By allowing a large margin of error for what may prove to be arbitrary or incorrect in such a calculation, the correction apparatus is, however, efficiently protected.

The embodiment described above is only an example which may be modified without going outside the scope of the present invention, which may be applied to all telegraphic systems whether wired or wireless functioning with correction currents for maintaining the synchronism.

I claim:

1. A telegraph system comprising the combination of a transmitting station and a receiving station, means at said transmitting station for periodically sending correcting signals which are adapted to operate a correcting mechanism at said receiving station to keep the transmitting and receiving devices in synchronism, and an arrangement at said receiving station for preventing the operation of said correcting mechanism unless a plurality of correcting signals are received at regular intervals of time.

2. A telegraph system comprising the combination of a transmitting station and a receiving station, means at said transmitting station for periodically sending correcting signals which are adapted to operate a correcting mechanism at said receiving station to keep the transmitting and receiving devices in synchronism, a receiving device at said receiving station adapted to periodically receive said correcting signals, and an arrangement at said receiving station for preventing the operation of said correcting mechanism unless a plurality of correcting signals are received at consecutive receptions of said receiving device.

3. A telegraph system comprising the combination of a transmitting station and a receiving station, a correcting distributor at said transmitting station to periodically transmit correcting signals, a corrected distributor at said receiving station adapted to periodically receive said correcting signals a correcting mechanism at said receiving sta-

tion adapted to correct said corrected distributor in accordance with the correcting signals to keep the correcting and corrected distributors running in synchronism, and an arrangement for preventing the operation of the correcting mechanism unless a plurality of correcting signals are received at consecutive correcting receptions of said corrected distributor.

30 4. A telegraph system as claimed in claim 2 wherein the arrangement is interposed between the correction contact of the corrected distributor and the correcting mechanism.

15 5. A telegraph system comprising the combination of a transmitting station and a receiving station, a correcting distributor at said transmitting station to periodically transmit correcting signals, a rotary corrected distributor at said receiving station, a correcting mechanism at said receiving station adapted to operate in accordance with said correcting signals to keep the two distributors in synchronism, a correction contact on said corrected distributor which is connected to said correcting mechanism and causes the operation of the correcting mechanism if a correcting signal arrives when the brushes of the corrected distributor are on this contact, and an arrangement interposed between said correction contact and said correcting mechanism to prevent the operation of the correcting mechanism unless a correcting signal is received at several consecutive revolutions of the corrected distributor.

35 6. A telegraph system comprising the combination of a transmitting station and a receiving station, a correcting distributor at said transmitting station to periodically transmit correcting signals, a rotary corrected distributor at said receiving station, a correcting mechanism at said receiving station adapted to operate in accordance with said correcting signals to keep the two distributors in synchronism, a correction contact on said corrected distributor which is connected to said correcting mechanism and causes the operation of the correcting mechanism if a correcting signal arrives when the brushes of the corrected distributor are on this contact, and an arrangement interposed between said correction contact and said correcting mechanism to store the first two correcting signals received at two consecutive revolutions of the corrected distributor, and only allow the correcting mechanism to operate if a third correcting signal is received at the next revolution of the corrected distributor.

60 7. In a telegraph system comprising a transmitting station and a receiving station, a correcting distributor at said transmitting station to periodically transmit correcting signals, a rotary corrected distributor at said receiving station, and a correcting

mechanism at said receiving station adapted to correct said corrected distributor in accordance with the received correcting signals, means for preventing the operation of the correcting mechanism by means of parasite impulses comprising an arrangement for preventing the operation of said correcting mechanism unless an impulse is received at several consecutive revolutions of the corrected distributor.

75 8. A telegraph system as claimed in claim 7, wherein the correcting mechanism can only operate if an impulse is received at three consecutive revolutions of the corrected distributor and wherein if, at the third revolution, an impulse does not arrive, the arrangement is restored to its normal position and requires three more impulses at consecutive revolutions of the corrected distributor to operate it.

85 9. In a telegraphic system in which a correcting signal is periodically sent to keep the transmitting and receiving devices in synchronism, an arrangement for preventing the operation of the correcting apparatus by parasite impulses comprising the combination of two electromagnets whose armatures are adapted to be mutually locked so that when either of said armatures is in the attracted position it is locked in said position by the other of said armatures until said other armature has been attracted in turn, means for operating the first electromagnet by the received impulses, means for periodically operating the second electromagnet by a local current, a rod member adapted to be moved step by step in accordance with the movements of the armature of said second electromagnet, a third electromagnet, a commutator for opening the circuit of said second electromagnet when its armature is attracted and diverting said local current through said third electromagnet, and a commutator for opening the circuit of said first electromagnet when said rod member has executed a predetermined number of steps, and diverting said received impulses through the correcting mechanism, said third electromagnet operating subsequently to restore the arrangement to its normal position, whether an impulse has been received or not.

10. In a telegraph system in which correcting signals are periodically sent to keep the transmitting and receiving devices in synchronism, said transmitting and receiving devices comprising rotary distributors, an arrangement as claimed in claim 9, wherein means are provided for operating the second electromagnet by a local current at each revolution of the receiving distributor, and wherein in the third electromagnet is adapted to operate at the revolution of said receiving distributor immediately following the diverting of the correcting impulses through the correcting mechanism, to restore the arrangement.

ment to its normal position whether an impulse has been received or not.

11. In a telegraph system comprising the combination of a transmitting station and a receiving station, a correcting distributor at said transmitting station adapted to periodically transmit correcting signals, a corrected distributor at said receiving station, a correcting mechanism adapted to correct said corrected distributor in accordance with the correcting signals transmitted from said transmitting station, and means for preventing the operation of said correcting mechanism by means of parasite impulses, said means comprising an arrangement whereby the operation of said correcting mechanism is prevented unless a plurality of correcting signals are received at regular intervals of time.

12. A telegraph system comprising the combination of a transmitting station and a receiving station, a correcting distributor at said transmitting station adapted to periodically transmit correcting signals, a rotary distributor at said receiving station adapted to be maintained substantially in synchronism with said correcting distributor at said transmitting station by means of a correcting mechanism at said receiving station, a correcting mechanism adapted to correct said rotary distributor in accordance with the correcting signals transmitted from said transmitting station, and means for preventing the operation of said correcting mechanism unless a plurality of correcting signals are received at consecutive revolutions of said rotary distributor.

13. A telegraph system comprising the combination of a transmitting station and a receiving station, a rotary distributor at said transmitting station adapted to periodically transmit correcting signals, a rotary distributor at said receiving station adapted to be maintained substantially in synchronism with said rotary distributor at said transmitting station by means of a correcting mechanism at said receiving station, a correcting mechanism adapted to correct said rotary distributor at said receiving station in accordance with the correcting signals transmitted from said transmitting station, and an arrangement, interposed between said rotary distributor and said correcting mechanism at said receiving station, adapted to prevent the operation of said correcting mechanism unless a plurality of correcting signals are received at consecutive revolutions of said receiving distributor.

In testimony whereof I have hereunto affixed my signature.

ANDRÉ LERY.
